UNITED STATES PATENT OFFICE.

CHARLES JOHN GIBBONS, OF NEW MILFORD, AND PERCY C. FARWELL, OF BRIDGEPORT,
CONNECTICUT.

GEAR-DRIVE FOR ROLLING-MILLS.

1,158,479.

Specification of Letters Patent.

Patented Nov. 2, 1915.

Application filed April 30, 1914. Serial No. 835,422.

To all whom it may concern:

Be it known that we, CHARLES J. GIBBONS, of New Milford, Litchfield county, Connecticut, and PERCY C. FARWELL, of Bridgeport, Fairfield county, Connecticut, citizens of the United States, have invented certain new and useful Improvements in Gear-Drives for Rolling-Mills, of which the following is a specification.

10 Our invention relates to new and useful improvements in gear drives for rolling mills, such as are used for rolling metals, rubber and other materials into bars, bands, strips, sheets, plates, and special shapes.

15 The objects of the invention are to produce an improved form of rolling mill drive for three high mills, so called, all of which is self-contained, and in which the pitch diameter of the roll driving pinions exceeds 20 the diameter of the driven rolls, thus obviating a recognized weakness in the present type of rolling mill drives; to include in our design an improved form of gearing and the relationship of the gears, one to the 25 other, which will permit and provide for the location of several rolling mills on each end of the drive, in a manner which will make it possible to employ one or all of the rolling mills at the same time and when 30 operating two or more of the rolling mills to more evenly distribute the load factor incidental thereto, thus materially eliminating the objectionable irregular rolling mill loads which are common with the present 35 ordinary forms of rolling mill drives whether driven by electric motor, steam engine or water power; to particularly construct said gear drive so that any number of said rolling mills may be arranged upon 40 and driven from each end of the drive and directly connected with the driving pinions of said gear drive, thus the better to balance the load, this being a direct advantage to the source of power. Further to provide 45 a self-contained drive for three high rolling mills, wherein there is a large anvil roll, a small friction work roll, and a large supporting roll for the small work roll, with roll driving pinions whose pitch diameter 50 is larger than the diameter of the driven rolls, whereby an increased amount of power or leverage is obtained, so that a greater amount of work may be produced with a given amount of initial power, and further 55 to so arrange said device as to insure an

economical self-contained gear drive for continuous mills in a simple, efficient and practical way; further to so design and arrange the parts that the roll driving pinions and the internal gear driving the same will be completely housed together and form a compact and protected driving mechanism.

With the above and other objects in view our invention resides and consists in the novel construction, arrangement and assemblage of parts shown upon the accompanying three sheets of drawings forming a part of this specification, upon which similar characters of reference designate like or corresponding parts throughout the several figures, and of which—

Figure 1 shows a top plan view of our improved form of rolling mill drive, the same being shown connected with a rolling mill such as it is designed to operate. Fig. 2 is an end or side view of the drive as seen from line 2 of Fig. 4. Fig. 3 is a detached side elevation of the large rotary gear member and the inclosed pinions operated thereby, and mounted upon the driving shafts to which the mills are coupled. Fig. 4 is a central vertical sectional view through the drive and showing a rolling mill connected to each side thereof, and Fig. 5 shows a central vertical longitudinal sectional view through a modified form of the drive and connected to a pair of mills as in Fig. 4.

It will be obvious that our improved form of drive like others of its class, may be operated from any suitable source of power, as for instance in the accompanying illustration we have shown the same operatively connected with a suitable electric motor 6. This motor is preferably mounted upon the same floor as the drive and mills, and its motor shaft 7 is connected with a pinion 8 that meshes directly with the drive.

Our improved form of drive is made possible through the employment of a particular relationship of gears mounted and arranged in the manner shown and which as before stated is adapted to be directly connected with and drives two or more rolling mills when set in alinement with each other, and upon the same or upon opposite sides of the drive. The driving member 9 is preferably in the form of a gear and is of a relatively large diameter and has its flanged or peripheral face cast or cut to form the outer or larger gear 10 which meshes with and is 110

driven by the pinion 8 before mentioned. The central or hub portion 11 of this wheel is finished to form a bearing 12 which is supported and rotatably operates in bearings 13-13 formed in housings 14-14 upon the opposite sides of the said driving member. These housings are mounted on a suitable bed plate 15 and are thus adapted to support and provide bearings for the hub 10 of the large driving member. Each of these housings may be formed in one or two parts and may include a base 16 and a cap 17 which is secured to the base by screw bolts 18. An opening 19 is left in each of these members of the uprights to form a guideway for bearing boxes or chucks 20 which are arranged in pairs one above the other, and one pair in each opening and in vertical alinement to provide bearings for shafts 22 and 23. A series of gear teeth 21 are formed in the inner face of the hub 11 of the large gear 9. Thus the large wheel as constructed forms both an external and an internal gear and has its annular operative bearing intermediate of the said external and internal gear faces, so as not to form any obstructions such as webs or inclosures across either side of the said internal gear, but is arranged in a way to leave the internal gear perfectly clear and free for operation past and around the connected parts.

The drive further includes two driven gear pinions 26 and 27 and shafts 22 and 23, which in practice aline with the roll shafts 35 of the rolling mill rolls and are connected with the usual form of coupling boxes 24 and spindles 25. These driven shafts 22 and 23 are journaled in the before mentioned bearing boxes 20 which as previously stated 40 are slidably mounted in the said housings. Provision being made to keep the small pinion gears 26 and 27 in proper mesh in the internal gear 21. Pinions 26 and 27 are mounted upon the respective driven shafts 22 and 23 and mesh with the internal gear 21 and are rotated, each in the same direction thereby. The relative size of the said pinions and internal gear are such as to permit of a free operation of the said pinions 45 and shafts inside of the opening through the large wheel and without interference of one pinion with the other.

From the foregoing construction it will be noted that the arrangement of all gears, pinions and parts is such as to insure a direct application of power from one part to the other in every instance where it is transmitted and that advantage is obtained by imparting the power from the small and rapidly driven pinion 8 upon the motor shaft 7 to the large external gear 10 and again by transmitting the power from the large internal gear 21 to the small pinions 26 and 27 which are driven in the same 60 direction and the speed ratio of the internal

gear 21 to the pinions 26 and 27 being about three to seven.

28 and 29 represent rolling mills which may be of the usual or any preferred construction. As illustrated these mills include 70 housings 30-30 in which boxes and bearings are placed to support the driven rolls 31 and 32 and friction or work roll 33. The wabbler ends of these driven rolls project through the standards so as to be directly connected with the drive or so that a second mill of like construction can be coupled to those shown or arranged next to the drive so as to operate two or more mills 75 from one drive and on each end thereof.

In Fig. 5 we have shown the annular bearings 13^a of the housings 14 shaped to form an external bearing instead of an internal bearing as in Fig. 4. The hub of the large gear in this form is flanged to 85 form annular internal bearings 12^a into which the before mentioned bearings 13^a extend for supporting the wheel. This modification thus forms a reverse construction of bearing from the preferred form, and one 90 which justly comes within the scope of our invention.

Our improved form of mechanism makes it possible to drive a single mill, a pair of mills or two or more pairs as the case may 95 require and from each end of the drive. We find in practice that the mills operate more economically and better if the same number are employed upon each side of the drive and which arrangement is made possible by our improved construction, wherein the two pinions and shafts are employed and both shafts extend throughout and clear of the main driving wheel in the manner shown and described.

From the foregoing it will be noted that we have produced a drive wherein the driving pinions (26 and 27) have a larger pitch diameter than the rolls 31 and 32 which they drive, which is a feature that so far as 100 we know has not been accomplished heretofore. This increased diameter adds materially to the life of the pinions and is a big factor in the rolling mill work.

Having thus described our invention what 115 we claim and desire to secure by Letters Patent is:—

1. In a rolling mill drive of the class described, the combination of a rotary driving member including an internal gear having 120 its central portion entirely open and free, a pair of pinions within the gear, shafts upon which the pinions are mounted and extending entirely through the said driving member.

2. In a rolling mill drive of the class described, the combination of a rotary member including an internal gear and having an external annular hub surrounding the said gear, bearings to receive and support the 130

- said hub, pinions meshing with the said internal gear, and a shaft extending through each of the said pinions and having their ends extended for connection to a rolling mill.
3. In a rolling mill drive of the class described, the combination of a rotary driving member including an internal gear having its central portions entirely open and free, a pair of pinions within the gear, couplings connected with the two sides of each pinion for connection with one or more rolling mills on one or both ends of said pinion shafts.
4. In a rolling mill drive of the class described, the combination of a rotary member including an internal gear and having an external annular hub surrounding the said gear, bearings to receive and support the said hub, pinions meshing with the said internal gear, and a shaft extending from each side of the said pinions for connection with a rolling mill.
5. In a rolling mill drive of the class described, the combination with a rotary driving member having an external and internal gear, a pair of driven shafts extending entirely through the central portion of said driven member and its internal gear, and pinions upon each of the said driving shafts that mesh with and are operated by the said internal gear.
6. In a rolling mill drive of the class described, the combination of a rotary member including an internal gear, a pinion within the gear, a shaft extending from each side of the gear, and connections on said shafts for attachment to a rolling mill.
7. In a rolling mill drive of the class described, the combination of a rotary member including an internal gear, a pair of pinions inside of the gear, shafts upon which the gears are mounted and extending outward on each side of the drive for the connection of a mill.
8. In a rolling mill drive of the class described, the combination of a rotary member including an internal and external gear and having an annular bearing surrounding the said internal gear, an upright upon each side of the rotary member to engage and support the said gear bearings, pinions operated by the said internal gears, and shafts for the said pinions extending through the said internal gear and having their opposite ends supported in the said uprights.
9. In a rolling mill drive of the class described, the combination of a pair of spaced uprights arranged side by side and each
- having an annular bearing upon its inner face, a rotary wheel member having a hub rotatably mounted in the said bearings and having a central opening through the said hub and an internal gear formed in the inner wall of said hub, one or more pinions meshing with the said gear and having spindles upon two sides that are supported in bearings of the two said uprights, and means for connecting both of said spindles with a rolling mill.
10. In a rolling mill drive of the class described, the combination with a large driving gear, of a pair of smaller gears driven thereby and arranged within the said larger gear, a pair of operating rolls each of which is in longitudinal alinement with the said smaller gears, the pitch diameter of the said smaller gears being of a larger diameter than that of the operating rolls.
11. In a rolling mill drive of the class described, the combination of a pair of small gears arranged side by side, a large gear surrounding and engaging the opposite and outer sides of the smaller gears, means for coupling the small gears to a pair of operating rolls when arranged in longitudinal alinement with the small gears, the said smaller gears being of a larger pitch diameter than that of the rolls to be connected therewith.
12. The combination with a three high rolling mill having a pair of operating rolls and a friction work roll, of a pair of gears one arranged in longitudinal alinement with each of said operating rolls and adapted to drive the said rolls the said gears being of a larger pitch diameter than that of the rolls, and an internal gear for operating the said pair of gears.
13. In a rolling mill drive of the class described, the combination of a pair of small gears arranged one above the other, a pair of operating rolls arranged in longitudinal alinement with the small gears and being of a smaller diameter than the pitch diameter of said small gears, and a driving gear connected to the outer and opposite sides of the said small gears for operating the same and the rolls.

Signed at New Milford in the county of Litchfield and State of Connecticut this 20th day of April A. D., 1914.
